(57) **CLAIM**

The ornamental design for a motorcycle as shown and described.

DESCRIPTION

FIG. 1 is a front elevation view of a motorcycle embodying my new design;

FIG. 2 is a top plan view thereof;

FIG. 3 is a left side elevation view thereof;

FIG. 4 is a right side elevation view thereof;

FIG. 5 is a rear elevation view thereof;

FIG. 6 is a top, front, and left side perspective view thereof;

FIG. 7 is a top, front, and right side perspective view thereof;

FIG. 8 is a top, rear, and right side perspective view thereof; and,

FIG. 9 is a top, rear, and left side perspective view thereof. The grayscale depicted in the drawings show contour or contrast in appearance, and does not represent any particular color, material, texture, or finish.

1 Claim, 9 Drawing Sheets
